UNITED STATES PATENT OFFICE

2,511,705

WAVE ACTUATED AIR COMPRESSING APPARATUS AND PROCESS

Dean Fletcher, Wildomar, and John H. Stinson
and Charles Gray, Elsinore, Calif.

Application December 29, 1948, Serial No. 67,982

1 Claim. (Cl. 230—65)

1

This invention relates to improvements in wave actuated air compressing apparatus, the primary object of the invention being to provide an improved wave actuated air compressing apparatus of the float type, which will utilize the force of the waves for operating an air compressing pump on its compressing stroke, the weight of the pontoons or floats, together with the receding movement of the water operating the compressing pump, in its suction stroke.

Another object of the invention is to provide an improved form and construction of wave actuated air compressing apparatus which may be positioned in any desirable place off shore where the pontoon floats will receive the full force of the waves of the body of water on which the device operates.

A further object of the invention is to provide an improved wave actuated air compressing apparatus which is highly efficient in operation and relatively inexpensive to manufacture and produce.

Other objects will appear as the description proceeds.

In the accompanying drawings which form a part of this application:

Figure 1 is a side elevational view of the improved wave actuated air compressing apparatus, constructed in accordance with the invention.

Fig. 2 is a plan view of the improved wave actuated air compressing apparatus illustrating two of the pontoons and compressors.

Fig. 3 is a front elevational view of the improved air compressing pump actuated float.

Fig. 4 is an enlarged detail view partly in section, showing the improved air compressing pump, the view being taken on the line 4—4 of Fig. 3.

Fig. 5 is a vertical fragmental sectional view through a pontoon or float illustrating the cushioning means of the compressor, the view being taken on line 5—5 of Fig. 1.

Fig. 6 is a sectional view taken on line 6—6 of Fig. 5.

Referring to the drawings in detail, the reference character 5 indicates a pair of barges arranged in parallel spaced relation with respect to each other, the barges being connected by upper and lower transversely disposed channel bars 6 and 7 respectively, whereby the barges are maintained in proper spaced relation with respect to each other.

Secured to the upper channel bars 6 and extending inwardly from points adjacent to the

outer ends of the channel bars, are inclined supports 8, which supports are bolted to the frames 9 which embody spaced channel bars 10 having their open sides disposed inwardly providing tracks, the lower ends of the channel bars 9 being connected with the I-beams 11 that extend from the bottoms of the barges, providing supports for the lower ends of the frames 9.

In Fig. 1 of the drawings we have shown a plurality of compressing units forming an important part of the invention. However, since these units are identical, and since the number of units may be varied to meet the requirements of use, only one of these units will be described in detail.

Each unit embodies a drum-like pontoon 12, which is of a length to fit between the inner surfaces of the inclined parallel channel bars 10 of the frame in which it moves, upper and lower shafts 13 being secured to the pontoon directly opposite to each other, on which the wheels 14 are mounted, the wheels being disposed at the ends of the shafts to run on the flanges of the channel bars 10, guiding the pontoon in its movement along the channel bars.

At the upper side of each pontoon are spaced ears 15 to which the piston rod 16 is pivotally connected, the piston rod operating within the cylinder 17 of the compressor which is mounted within openings formed in the supporting bars 18 and 19 that extend between the channel bars 10. As shown, the upper end of the cylinder 17 extends beyond the supporting bar 19, to which end is connected a flexible tube or hose 20, that in turn connects with the pipe 21 that leads into the compression tank 22.

Extending into the upper end of the cylinder 17, is the cylindrical valve chamber 22' having the valve seat 23 against which the valve 24 seats, the valve 24 being held to its seat by means of the coiled spring 25, that is secured around the valve stem 26 which in turn operates through an opening formed in the cross bar 27. The piston 28 is mounted on the upper end of the piston rod 16, and on its suction stroke, operates to draw air into the cylinder 17 through the valve 24, the valve being unseated by the suction created by the piston 28. An inlet pipe 29 connects with the cylindrical valve chamber 22 and through which air enters the valve chamber.

Directly above the piston 28, and disposed at a point approximately at the limit of the compression stroke of the piston, is a valve chamber 30 having a valve seat 31 against which the valve

32 operates, the valve 32 seating on the suction stroke of the piston 28. This valve 32 will move to its open position during the compression stroke of the piston, to allow air to be forced through the valve chamber 30 and into the end of the cylinder above the supporting bar 19. The tension of the spring 33 will under normal conditions, act to return the valve 32 to its closed position.

Arranged within each of the channel bars 10 at opposite sides of each frame, are cushioning members 34, each of which comprises an upper stationary plate 35 held in position by means of the brackets 36 that are adjustable longitudinally of the channel bars 10, by means of the bolts 31 that pass through openings of the brackets and are held within any one of the openings 38. Since these openings are arranged with respect to the movements of the pontoons, it will be seen that by adjusting the stationary plate, the tension of the springs 39 will contact therewith. These springs 39 are coiled around the pins 40 that have their lower ends threaded and disposed in threaded openings of the blocks 41, the blocks 41 being formed with curved lower edges to receive the curved edges of the wheels 14, relieving the entire structure of undue strain which would ordinarily be directed thereto by the movement of the pontoons to the limits of the upward and downward positions. It will thus be understood that a spring cushioning device 34 is used at the lower ends of the channel bars 10 for contact by the rollers of the lower sides of the pontoons, when they move downwardly.

From the foregoing it will be seen that due to the construction shown and described, we have provided an air compressor embodying one or more cylinders and pistons, the pistons being operated by the vertical movements of the pontoons which in turn move with the waves for moving the pistons for compressing air in their cylinders as described.

Having thus described the invention, what is claimed is:

A wave-operated compressor comprising spaced

floating supports, transversely disposed bars connecting the supports, inclined supports rising from the transversely disposed bars, a rectangular frame mounted between the supports and secured thereto, said frame embodying channel bars having their open sides disposed inwardly providing tracks, said tracks extending between the spaced floats, a pontoon mounted between the spaced channel bars, shafts extending across the pontoon, wheels mounted on the ends of the shafts and movable along the channel bars, guiding the pontoon in its movements, a cylinder mounted within the frame, a piston operating within the cylinder, a rod connected with said piston and having pivotal connection with the pontoon whereby movement of the pontoon operates the piston within the cylinder compressing air in the cylinder, valves controlling the passage of air to and from said cylinder, a storage tank, a pipe connected with the cylinder and storage tank whereby air is compressed in the storage tank by said piston operating within the cylinder, cushioning members disposed within the channel bars and engageable by said wheels whereby movement of the pontoon is restricted and said pontoon being so constructed and arranged for movement by contact with waves moving thereunder.
